NILS D. LEVIN, OF COLUMBUS, OHIO, ASSIGNOR TO THE JEFFREY MANUFACTURING COMPANY, OF COLUMBUS, OHIO, A CORPORATION OF OHIO.

RHEOSTAT.

1,267,879.

Specification of Letters Patent. Patented May 28, 1918.

Application filed August 17, 1915. Serial No. 45,961.

To all whom it may concern:

Be it known that I, NILS D. LEVIN, a citizen of the United States, residing at Columbus, in the county of Franklin and State of Ohio, have invented certain new and useful Improvements in Rheostats, of which the following is a specification, reference being had therein to the accompanying drawing.

This invention relates to improvements in 10 rheostats of the class in which the resistance elements are each built up of units adapted to be arranged closely together in a series of indefinite number, the parts being so constructed and related that units can be added 15 in a series one after another until a resistance of a predetermined degree is attained.

Much difficulty has been experienced, and 20 but little success achieved, in providing artificial resistances for certain lines of electric motor apparatus; for example, such motors as are used in coal mine work.

In mines, and similar places, the room within which electric motors and their adjuncts must be contained is limited, and the 25 space restricted. The difficulty referred to arises from the necessity of providing mechanical apparatus which can be frequently moved about, in the contracted space in the mine rooms, and which shall be composed 30 of parts that will be as efficient as possible in respect to the development of power, and which shall, at the same time, be durable and have sufficient strength.

Of the space available around such mine 35 apparatus (as mining machines, electric locomotives, and the like) for their motors and their adjuncts, that part which can be allowed for such devices as rheostats is particularly restricted. It is not only necessary 40 to provide rheostat or resistance mechanism which will be efficient in the controlling of powerful currents, but which will allow rapid dissipation of heat, and have the parts so arranged that the radiating surfaces will 45 be separated sufficiently to permit such dissipation.

The object of the present invention is to 50 provide a resistance device which will have all of its parts compactly arranged in restricted space and yet will be sufficiently strong and durable for the work to which it is subjected, which will insure perfect insulation at all times, will have the parts accessible for repair and renewal, will have

the conducting elements exposed to permit 55 free radiation of heat, can be initially made at minimum cost, and can be readily repaired at points remote from the shops and without skilled labor.

Figure 1 is a front elevation of a resist- 60 ance device embodying my improvements;

Fig. 2 is a section on the line 2—2 of Fig. 1;

Fig. 3 is a side view of that part of the 65 device which is shown in Fig. 1;

Fig. 4 is a perspective of one of the 70 insulating and conductor-holding boxes.

The resistance devices, proper, consist of metallic strips 1 and 2. They are preferably formed by cutting sections from sheets or ribbons of metal of suitable length and composition. These sections are of the same width, and, as concerns their length, they are of two sets, all those of each set being of equal length. They are thin and flat, and 75 hence rapidly dissipate heat, which quickly reaches the surfaces and escapes from the latter. Being relatively wide, they insure a conducting contact when one is placed against another.

They are arranged in layers one above another, each layer comprising two of the strips 1 and two of those indicated at 2; the four parts of each layer being analogous to the four side parts of a square coil. When 80 arranged as shown the current passes first through one of the long strips 1, then through one of the short strips 2, then through the other long strip 1, and then through the second strip 2. The latter is, 85 at its end, insulated from the initial strip 1 of its layer, but contacts with the strip 1 of the next layer. The end parts of the second layer are insulated from the corners of the first layer and at its termination it is insulated from its initial strip 1 of its own 90 layer. And so on throughout the series.

After enough of the layers have been superposed to provide the predetermined degree of resistance, all of the strips 1 and 2, 100 and their intermediate insulation elements between the layers, are clamped together by devices that exert pressure on lines perpendicular to the faces of the strips.

The structure so built up constitutes the 105 essential part of the resistance device. It can be mounted in any suitable holder and protecting casing.

I have devised an improved insulating holder for such a resistance element, and have illustrated it in the drawings.

17 indicates a metallic box-like casing formed with the walls 4 and 5 and the intermediate side walls 3, these inclosing a chamber or a space which is open on the front and rear. Or the casing can be formed with two chambers or receiving spaces, in which case the wall 5 will be intermediate of two walls such as indicated at 4.

A suitable number of pedestals or lugs 6 are provided, preferably by casting them integral with the casing, which permit the fastening thereof to the motor or other part of the mechanism, and which are offset in such way as to provide an open space between the resistance elements and the surface, indicated by the dotted line 6^a, of the part to which the casing is attached. At 4^a flanges are formed on the casing to serve as shoulders or seats.

In each of the chambers in the casing there are fitted two box-like retainers 7 of insulating material, such as porcelain. Each has a continuous back wall 18, continuous side walls 19, and inclosed or continuous end wall 12. The front wall is cut away, as shown at 20, the remaining parts of this wall constituting flanges, as at 8 and 10. On the back wall 18 opposite the central part of the opening 20 there is a rib 9 projecting somewhat forward from the wall 18. The parts 8, 10, 9, 18 and 19 are all preferably integral. There is no wall at the end of the box opposite to the closed wall 12.

It will be seen that at each side of this box-like retainer there are two partially inclosed chambers 21.

40 The distance between the plane of the side face of the rib 9 and the plane of the edge face of the flange 8, or of the flange 10, is equal to the width of a resistance strip; and the distance from the plane of the outer edge of the rib 9 to the plane of the inner faces of the flanges 8 and 10 is also equal to the width of a strip.

Two of these boxes 7 are placed in the casing 17 with their openings 20 opposite to each other, one of the side walls 19 of each box abutting against a flange 4^a on the casing. After placing the two boxes in the casing one of the resistance structures above described can be put in place by having its ends inserted into the chambers in the boxes so as to be positioned substantially as shown in Fig. 3.

Or, the resistance element, as an entirety, can be built up, piece by piece, in the insulating boxes after the latter are set in the casing. In doing this two of the long strips 1, 1 are dropped flatwise through the open end of the boxes until they rest upon the insulating walls 12. Then one of the 65 shorter strips 2 is placed across their ends.

Then a square insulating strip or block 11 is placed upon the initial end of the first strip 1. Then a conductor strip 2 is laid with one end on the second conductor strip of the bottom layer, and with its other end upon the insulating piece 11. Then three of the strips or squares 11 of insulation are placed in the chambers 21, at each of the three other corners of the layer, and another series of the strips 1 and 2 are put 75 in position to form a second layer.

In this way, with alternating layers of conducting strips and insulation pieces, the resistance element is built up until the total length of the conductor provided by the strips is of the required length.

For each resistance element the two strips 1 at the ends of the series are respectively provided with terminal connectors 16.

After the pile has been completed outside 85 insulating strips or plates 14 are placed upon the top of a pile, one at each end of the resistance element, and outside of these reinforcing or pressure plates 15 are placed. Against the latter binding screws 13 have 90 bearing, these being seated in threaded apertures in the upper side wall of the casing. When the screws are tightly set they clamp together all of the components of the resistance pile, and also bind each of 95 the box-like retainers 7 tightly in place in the casing.

The boxes 7 are a considerable distance apart, and the chamber in the casing being open on opposite sides, the air can freely 100 circulate through the structure for rapidly carrying away the heat that comes to, and radiates from, the surfaces of the strips.

There are no small connecting screws or similar parts for binding together the different elements of the resistance; the device is compact, and the parts cannot be rattled or shaken loose. As an entirety, the resistance occupies but small space. In case of damage any part can be readily withdrawn 110 and a new one substituted without skilled labor or requiring work at the shops.

What I claim is:

1. The herein described resistance element composed of a series of insulated layers each layer comprising longitudinal strips and transverse strips arranged to leave projections at the ends of the longitudinal strips and having a freely separable engagement therewith, an insulating retainer arranged to engage with the transverse strips and with the projecting ends of the longitudinal strips to prevent their displacement in relation to each other, and means for pressing the strips together. 115

2. In a rheostat, a resistance element having a series of insulated layers each layer composed of two longitudinal strips and two transverse strips respectively situated inside of the adjacent ends of the longitudi- 130

- nal strips, each strip having a freely separable engagement with adjacent strips, insulating retainers for the end parts of the element having chambers and flanges substantially as set forth to engage with the longitudinal strips and the transverse strips to prevent their lateral displacement in relation to each other, and means for pressing the strips together.
10. 3. In a rheostat, the combination with a series of resistance strips arranged end to end to provide an electric circuit section, each strip being positioned to have its longitudinal lines transverse to the longitudinal lines of adjacent strips whereby the series of strips surrounds an insulating space, of insulating retainers having recesses wherein the ends of the strips are loosely fitted and by which the strips are held against lateral displacement, and means for pressing the strips together on lines transverse to their wider faces.
4. In a rheostat, the combination with a series of conducting strips arranged end to end to form a circuit section throughout the series and so disposed as to form two side sets of strips and two end sets, the four sets surrounding a parallel side chamber, and all of the strips of the end sets being transverse to those of the side sets, insulating retainers which loosely engage the overlapping ends of the strips and hold them against lateral displacement, and clamping devices acting to hold all of the strips in predetermined position.
5. In a rheostat, the combination of a series of insulating layers of resistance material, each layer composed of a series of elongated relatively thin strips, each strip having freely separable engagement of its wider faces with faces of adjoining strips, insulating holders wherein the ends of the said strips are seated and which lock the ends of the said strips against displacement relative to each other, and means for pressing the strips together, substantially as set forth.
6. In a rheostat, a series of insulated layers of resistance material, each layer composed of a series of strips having freely separable engagement with each other, insulating retainers for the ends of the strips and provided with means for preventing the strips from being displaced laterally, in relation to each other, and means for pressing the strips together.
7. In a rheostat, the combination of a series of flat elongated relatively thin resistance strips arranged to have their wider faces freely separably engage with each other, insulating retaining devices engaging the edges of the end parts of the strips to secure them against lateral displacement, a casing surrounding said strips and retaining devices, and pressure devices for locking the casing, the strips and the retaining devices rigidly together.

In testimony whereof I affix my signature in presence of two witnesses.

NILS D. LEVIN.
